UNITED STATES PATENT OFFICE.

ALLEN JOHNSTON, OF OTTUMWA, IOWA.

METAL-SCREW MACHINE.

SPECIFICATION forming part of Letters Patent No. 293,176, dated February 5, 1884.

Application filed July 31, 1883. (No model.)

To all whom it may concern:

Be it known that I, ALLEN JOHNSTON, of Ottumwa, in the county of Wapello and State of Iowa, have invented a new and useful Improvement in Metal-Screw Machines, which improvement is fully set forth in the following specification.

This invention relates more particularly to machines for making screws from a long rod or screw-stock by a series of operations performed automatically; but it is in part applicable to machines not wholly automatic in their action, and to machines for making other articles.

It consists, first, in the combination, with the threading-die, of a pointing-tool separately supported, and arranged to project from the rear into the hollow center of the die. Heretofore a pointing-tool has been combined with a threading-die, the same being supported in the shank of the die or threading-tool, and connected therewith by a spline and groove, so that neither can turn independently of the other. The pointing-instrument, or cutter for shaping the point, and the die or cutter for turning the thread, are, in fact, so connected as to form one tool. In this invention they are substantially separate tools, but adapted for conjoint operation. This part of the invention also comprises the combination, with a rotary die, of a non-rotating pointing-tool arranged in line with the axis of the die. One of the principal advantages of supporting the pointing-tool separately from the die by means outside the same is, that thereby the two tools may be adapted to cut at different speeds. Where the pointing-instrument is connected with the shank of the die, as heretofore, the movement of rotation around the blank or screw-stock is the same for both die and pointing-instrument, and if the latter be held from independent longitudinal movement it must advance at equal speed with the die, and turn off the end of the blank as fast as it is threaded. To obviate the last difficulty, the pointing-instrument has heretofore been held to its work by elastic or yielding pressure, and not positively. The present improvement renders it unnecessary to resort to this expedient, (which has the disadvantage of leaving the screws unequal in length, or, at least, being liable to do so,) since the pointing-tool may be held to its work posi-

tively. It will be shown herein as thus held to its work.

The invention secondly consists in combining the mechanism for threading the screw stock or blank and pointing the same while the die is on the screw with mechanism for turning down the rod in advance of the threading-die, and, in part at least, simultaneously with the threading operation. This latter mechanism may be of the special construction shown in Letters Patent No. 269,790, granted to me December 26, 1882, or of other suitable construction adapted to the purpose, such as that hereinafter described.

The invention thirdly consists in mechanism for withdrawing the turning-down tool, after its cutting is accomplished, by moving it backward a short distance and then aside, thus leaving the under side of the head smooth and without burr. In my above-mentioned patent the slide carrying the turning-down tool moves in oblique ways. This part of the invention may be considered an improvement on that arrangement.

The invention fourthly consists in an adjustable length-gage supported on the machine-frame or stationary part of the machine, and movable across the axis of the chuck, in combination with the mechanism for relieving and restoring the bite of the chuck-jaws and for automatically introducing the gage in front of the chuck when so relieved. A spring or weight advances the long rod or screw-stock at this moment. The adjustment has for its object to enable wear to be taken up or compensated for, and also to regulate the feed of the rod or stock to suit different sizes of screws. In Letters Patent No. 269,791, granted to me December 26, 1882, a similar combination is described without the feature of adjustment of the length-gage. This part of the invention may therefore be considered as an improvement upon the construction therein. It comprises, also, the supporting of the length-gage upon a journal pin or shaft, instead of in ways or grooves, as shown in said patent. It is obvious that the journal pin or shaft could be used even if the feature of adjustment be omitted; but its use allows the adjustment to be most easily effected.

The invention fifthly consists in retaining,

or retaining and adjusting, the jaws of a screw-cutting die having the jaws formed in one piece by pressure applied at the points on the periphery, opposite or about opposite the cutting-edges of each jaw, the other parts of the jaw being left free or comparatively free, so that the jaws are by unequal application of pressure twisted slightly on their longitudinal axes, and the cutting-edges thus brought nearer the center, so as to secure a clearance for the die. Preferably the jaws are held in by a ring screwed thereon, as described in the patent first referred to, and the application of the pressure to the jaws on the side of the cutting-edges is secured by cutting away each jaw except on that side; but the jaws could be held in by a plain ring driven onto the die, or by a split ring, or by other means, and the application of pressure to the jaws at one side, instead of equally all over the back, could be secured, without cutting them away on the outside, by having suitable projections on the jaws or on the devices for holding them in. The advantage attained by this improvement is that the die cuts easier and lasts longer. The jaws may be straight on one side and inclined on the other, as described in my first-named patent; or they may be inclined on both sides. The number of jaws on the die may be varied.

30 The invention further comprises certain particular constructions and combinations, hereinafter specified, among which the following may be briefly mentioned, to wit: the supporting of the turning-down tool on a rocking-shaft, the construction of the mechanism for revolving the threading-die so as to have an axial opening for the introduction of the pointing-tool, the supporting of the die upon an auxiliary slide carried by the main longitudinal slide upon which the pointing-tool is independently supported, and a slotted tube for supporting the rear end of the rod or screw stock which projects beyond the end of the chuck-spindle.

45 The following is a description of the best mode which I have contemplated of applying the principle of the invention, reference being had to the accompanying drawings, which form a part of this specification.

50 Figure 1 is a vertical longitudinal section of an automatic screw-machine constructed in accordance with the invention; Fig. 1^a, a similar view of a part at the extreme left of the machine as viewed in Fig. 1 and omitted from said figure; Fig. 2, a plan (partly in horizontal section on line x x, Fig. 1) of the end of the machine which carries the cutting-tools; and Figs. 3, 4, 5, 6, and 7, vertical cross-sections on lines y y, z z, v v, w w, and t t, respectively, 60 and in elevation, looking in the direction of the arrows upon each section-line. Fig. 8 is a partial view, in longitudinal section, in a plane back of that of Fig. 1. Figs. 9 and 10 are respectively a face view and a perspective of the screw-cutting die detached.

The main or cam shaft A is journaled in bearings in the machine-frame B, and is driven

from the chuck-spindle C through a train of spur-gears, 1, 2, 3, 4, 5, 6, 7, 8, and 9, the chuck-spindle being revolved by a belt on pulley D. The chuck is or may be of any ordinary or suitable construction. As shown, it has a solid head, a, and contains a sliding tube, b, having a series of wedges formed on the front (right-hand, Fig. 1) end thereof, a spring, c, for pressing forward said tube b, a block or slotted tube, c², fixed in the head and forming stay-pieces between the wedges, and chuck-jaws d, formed in one piece and screwed at the rear end into said block, as fully described in Letters Patent No. 261,816, granted to me July 25, 1882. The friction-tube of said patent has been omitted; but it or other suitable friction devices may be used. The sliding tube b is at intervals withdrawn through 85 the lever E, pivoted to the machine-frame by the cam F on shaft A, and when released by said cam is restored by the spring c. Other mechanism of ordinary or suitable construction for releasing and restoring the bite of the 90 chuck-jaws could be used instead. When the bite of the jaws is released, the rod or stock e is advanced by the weight G, which is suspended in the bight of a cord, f, attached at one end to a stationary part of the machine, 95 and, after passing over pulleys or through guides, connected at the other end with the rod or screw-stock. The rear end of the said rod or screw-stock is supported loosely in the tube H, which is supported by brackets from the parallel bar I, fixed to the machine-frame, and is slotted underneath to allow the passage of the projection or arm g of the slide K*. It is through this slide that the cord f is connected with the rod or screw-stock, it (the 100 cord) being fastened in the projection or arm g, and the end of the slide bearing against the end of the screw-stock, so as to advance it when required. The slide, as shown, is in the form of a rod equal or about equal in diameter to the screw-stock e, and the projection or arm g is at the rear end of it. The object of this is to enable the slide or rod to enter the hollow chuck-spindle and advance the screw-stock until it is all or nearly all used up. It 115 is not, however, essential to use a feed-rod, since a succeeding screw-stock will push along the one in front of it after the outer end of the latter has entered the chuck-spindle. The distance which the screw-stock shall be advanced at each feed is determined by the length-gage K, which is supported on the stationary journal pin or shaft L, Figs. 2, 5, and 6, and is vibrated thereon across the axis of the chuck by the crank-pin h on the disk M, which 120 is keyed to the main or cam shaft A. The spiral tension-spring N removes it from in front of the chuck when it is released by the crank-pin h. Of course this release takes place when the bite of the chuck-jaws has 125 been restored. The hub of the gage is free to turn on the journal-pin L, but is prevented from movement lengthwise thereof by the nuts i on either side of the hub. These nuts, be-

ing adjustable, permit the adjustment of the length-gage. The crank-pin *h* is of such length and is so arranged that it strikes the lower end of the gage in all its positions of adjustment. The journal-pin *L* fits at the ends in recesses in the machine-frame, and is held from endwise motion by the nuts *k*, which are screwed up after the journal-pin has been inserted in the recesses. The slide *P*, which carries the turning-down tool *Q*, the die or threading tool *R*, and the pointing-tool *S*, is reciprocated in longitudinal ways of the machine-frame by the cam-groove *l* in the periphery of drum *T*, which is keyed on the main shaft *A*. A pin, *m*, fixed in said slide *P*, projects into the cam-groove *l*. The turning-down tool *Q* is not carried directly by the longitudinal slide *P*, but is held in an arm, *n*, of the rock-shaft *U*, which is journaled in bearings in said slide *P*. The rock-shaft *U* at its outer (right-hand, Figs. 1 and 2) end is turned down and threaded with a coarse, strong thread, and it is provided at the inner end of the threaded portion with a tooth, *p*. Upon the threaded portion is a nut or internally-threaded sleeve, *W*, which is prevented from end motion by the fixed collar *q*, between it and the holding-screw *r*, but is free to turn with the rock-shaft, and to a slight extent independently of it, the independent movement producing through the screw-thread a slight longitudinal movement of the rock-shaft. There is a tooth, *s*, on sleeve *W* corresponding to the tooth *p* on the rock-shaft. On the under side of the rock-shaft is a projection, *t**, which is held normally against the stop-screw *u* by a spiral compression-spring, *X*, inclosed in the two-part casing *a* *a*'. (See Fig. 3.) The lower part, *a**, of the casing is free to slide upon the part *a*', and has at its lower end a spherical head, which fits in a spherical recess in the projection *t**, thus making a universal joint at that point, while the upper end of the part *a*' is pointed and fits in a conical recess in the wall of the slide. The casing thus adapts itself to all the movements of the rock-shaft. When the projection *t** is against the stop *u*, as shown, the turning-down tool will be thrown forward in the proper position for turning down the rod or screw-stock. The proper position can be attained with great nicety by the adjustment of the stop *u* and the proper setting of the tool *Q* in arm *n*. The sleeve *W* is provided with a depending arm, *b*', which projects into the path of the arc-shaped cam *Y*, bolted to and movable with the disk *Z*, the latter being fixed to and revolving with the drum *T* upon the main shaft *A*. The cam or arc *Y*, striking the arm *b*', turns the sleeve *W* until the tooth *s* strikes the tooth *p*, when it turns also the rock-shaft *U*, moving the turning-down tool *Q* away from the screw-stock. While the cam or arc *Y* is passing under the arm *b*', it retains the turning-down tool in this position, and during this time the slide *P* (and with it, of course, the sleeve *W*, rock-shaft *U* and turning-down tool) is returned by the cam *l*.

When the arm *b*' is released by the cam or arc *Y*, the spring *X*, aided by the spiral tension-spring *A*', returns the rock-shaft and sleeve. After the rock-shaft is stopped by the screw *u*, the spring *A*' turns the sleeve *W* a little farther, so that when the parts are at rest there is a space left between the teeth *s* and *p*, as shown. The object of this is to allow the sleeve *W* a slight rotation independent of the rock-shaft, so as (by means of the screw-thread) to move the rock-shaft endwise, and thus withdraw the turning-down tool from the head of the newly-formed screw before it is moved aside by the further rotation of the sleeve *W*. The die *R* or threading-tool is supported on an auxiliary slide, *B*', movable in longitudinal ways of the slide *P*. The die is hollow, and has screw-cutting jaws formed integral therewith and adjusted by a ring, *11*. Each jaw is cut away on the exterior at *12*, (see Figs. 9 and 10,) leaving the pressure of the ring *11* upon the points *13* opposite the cutting-edges *14* of the die, or, in other words, upon the cutting or front side of the jaws. Thus the cutting-edges *14* are held in, while the farther edges *15* may spring out slightly, the pressure of the ring *11* thus giving a slight twist to the jaws and bringing the cutting-edges *14* nearer the center. This position gives a clearance to the die, which causes it to cut the thread easier and makes it last longer. The exterior threaded portion of the jaws is conical, so that by turning the ring *11* they may be brought nearer to or be allowed to spring out from the center. The base of the die is bored large enough to receive within it the pointing-tool *S*, and it is secured to a support, which is perforated for the same purpose. If it be desired to use the threading and pointing tools in a machine wherein the die does not rotate, it is obvious that this support is or may be non-rotatory; but if the die is to rotate, as in the machine shown, and as it is preferred to do, it is secured in a revolving support, such as the annular wheel or gear *C*. As shown, the die has an exterior flange, *c*', which is held by the annular screw *d*', and is further engaged by the pin *e*', fitting into a notch in the flange, and effectually preventing the die from turning independently of its support. The gear *C* is journaled in the head of slide *B*', and is revolved at the proper times from the short shaft *D*' through the clutch-piece *E*', turning with the shaft *D*', and the clutch-piece *F*', fixed to the sleeve *G*', and carrying the annular gear *H*', which meshes with the gear *C*. The clutch-piece *E*' has its bearing in the barrel *G*», fixed to the main slide *P*, and is held from endwise movement independent of said barrel by a nut on the end of the said clutch-piece, while the clutch-piece *F*', sleeve *G*', and gear *H*» are movable with the auxiliary slide *B*'. The two clutch-pieces are normally held in engagement by the spiral compression-spring *K*', (shown in dotted lines, Fig. 1, and in full in Fig. 8,) placed in a recess in the auxiliary slide *B*', and confined

between the screw g' , Figs. 1, 3, and 8, tapped into the outer end of the recess, and the pin f' , Figs. 1, 4, and 8, fixed in the main slide P , and passing through a slot in the slide B' , and 5 across the recess therein. The clutch-piece E' is connected with the shaft D' by a spline and groove, or equivalent connection, so that it revolves with said shaft, but is at the same time free to move lengthwise thereof. The 10 shaft D' is driven from the gear I' on the chuck-spindle through the pinion L' , fixed to the end of the shaft, and has a continuous rotary but no endwise movement. A non-rotating clutch-piece, M' , surrounds the sleeve G' on the opposite side of the clutch-piece F' from the clutch-piece E' . It is pressed in the direction of said clutch-piece F' by the spiral compression-spring N' , and is prevented from rotating by the screw or pin h' , which fits in a 15 slot, t' , and which serves also to limit the movement of the clutch-piece M' under the pressure of the spring N' . During the advance of the slide P the clutch-piece F' engages the clutch-piece E' and the die R is 20 revolved in the same direction as the chuck, but at a higher speed, so as to cut the thread on the portion of the rod or screw-stock which has just been reduced by the turning-down tool. When the thread is cut, the main slide P is 25 drawn sharply back by the cam l , and the die R being held by its engagement with the thread, the auxiliary slide B' , together with the sleeve G' and clutch-piece F' , are held from endwise movement. The clutch-piece E' , being 30 carried with the main slide, is thus disengaged, and the die is allowed to revolve with the chuck until the non-rotative clutch-piece M' , which also moves back with the main slide P , engages the piece F' , when the rotation 35 of the die is arrested, and the continued revolution of the chuck unthreads it. As soon as the die is released from the thread, the spring K' immediately causes a re-engagement of the clutch-piece E' , and the rotation 40 of the die is resumed. The pointing-tool S is supported on a cross-piece, P' , bolted to the main slide P . It is in line with the screw-stock, and has its end of the form adapted to give the desired shape to the point of the 45 screw. It projects through the annular wheel or gear C' into the base of the hollow die R . The cutting-off tool Q' , for removing the newly-formed screw from the rod or screw-stock, is carried by a cross-slide, R' , supported in ways 50 of the machine-frame, and reciprocated by the cam r' , formed on the periphery of the drum T , through the bent lever S' , fulcrumed to a bracket which is bolted to the machine-frame, and the link or connecting-rod T' . The tool 55 itself is supported on an auxiliary slide, U' , which is adjustable on the slide R' by the screw W' , Fig. 6.

The general operation of the machine as a 60 whole will now be described, it being assumed that the rod or screw-stock has been inserted between the jaws of the chuck, and has been connected properly with the feeding-weight

70 G, and that the cutting-off tool Q' has just severed a screw. As soon as the slide R' and the cutting-off tool Q' are sufficiently withdrawn by the cam r' , lever S' , and link T' , the length-gage K is turned by the crank-pin h across the axis of the chuck, and at the same time the pressure of the chuck-jaws d is released by the withdrawal of the sliding tube b by means of the cam F and lever E , so that 75 the feeding-weight G advances the rod or screw-stock until the end strikes the length-gage K , now immediately in front of the chuck. While the length-gage is still retained 80 in position by the crank-pin h , the sliding tube b is returned by its spring e , and the chuck-jaws are closed upon the rod or screw-stock, so that it is held firmly by and revolves with the chuck and chuck-spindle. The slide P , 85 together with the tools carried thereby, is now advanced by the cam l . The turning-down tool Q first comes into action and reduces the end of the rod or screw-stock. After it has 90 finished a sufficient distance, and before it has finished its operation, the threading-die R is brought into action and commences to cut the thread, it being revolved by the gears $I' L'$, shaft D' , clutch-pieces $E' F'$, sleeve G' , and gears $H' C'$ in the same direction as the chuck 95 and rod or screw-stock held therein, but at a higher speed. The turning-down tool and threading-die then proceed together. As the last part of the thread is being cut, the pointing-tool also comes into action and shapes the 100 point. As soon as the turning-down operation is finished, which may be at the same time with the threading operation, or it may be sooner, the arc-shaped cam Y turns the sleeve W , which first moves the rock-shaft U and 105 turning-down tool Q backward, so that the tool is clear of the newly-cut shoulder or screw-head, and then turns the rock-shaft and moves the tool aside. If the screw has then 110 been threaded as far as desired, the motion of the slide P is reversed; otherwise it continues until the thread has been extended as far as desired—it may be to the very head. During 115 this time, and during the reverse movement of the slide P , the turning-down tool is held away from the rod or screw-stock by the cam or arc Y . If the threading is to continue after the turning down has been finished, the pointing-tool is of course properly set to come into 120 action at the end of the threading operation. The return of the slide P disengages the clutch-piece E' , and by engaging the clutch M' stops the rotation of the die and unthreads it. When the die is clear of the rod or screw-stock, the cutting-off tool Q' is advanced to 125 sever the newly-formed screw, when the operations proceed as before.

It is obvious that modifications may be made in details without departing from the spirit of the invention, and that parts of the invention may be used separately. For example, the improved arrangement of die and pointing-tool could be used in machines for threading blanks, a suitable chuck and feed for hold-

ing and feeding a series of separate blanks being substituted for the one shown. Such chucks and feeds are well known. The tools also could be brought into operation by hand instead of automatically. The arrangement could be used in machines in which the chuck moves instead of the tools, as in that described in my Patent No. 267,214, dated November 7, 1882, and it could be used also in other styles of machine.

Automatic mechanism for feeding and bringing the tools into action is much preferred to that operated in whole or in part by hand, and its use in combination with the other elements is considered a special feature of improvement.

The length-gage could be used in various kinds of machines for turning or otherwise forming articles from the end of a long rod, and so with the other improvements.

Having now fully described my said invention and the manner of carrying the same into effect, what I claim is—

1. The combination, with the chuck, the screw-cutting die, and the pointing-tool arranged in line with the axis of the die, of the devices to which said pointing-tool is attached, the said devices being disconnected from the body of said die, so that the pointing-tool constitutes a separate tool, and may by suitable mechanism be made to cut at a different speed from that of the die, substantially as described.

2. The combination, with the chuck, die, and pointing-tool, of the supporting and operating mechanism, substantially as described, whereby the pointing-tool is brought into action while the die is on the screw-stock, and is made to cut the latter at a different speed of rotation from that of the die, as set forth.

3. The hollow screw-cutting die having the cutting-jaws formed in one piece with the body of the die, and provided with an opening in said body of greater diameter than the space between the cutting-edges, in combination with the annular or perforated support for holding the die by the periphery, as explained, so that a pointing-tool can be introduced through said opening into position for acting upon the stock in process of threading, substantially as described.

4. The combination, with the chuck, the die, and the pointing-tool arranged in line with the die, of the mechanism for holding the pointing-tool to its work rigidly and positively instead of by yielding pressure, substantially as described.

5. The combination of the rotatory screw-cutting die, the rotating chuck, and the non-rotating pointing-tool, substantially as described.

6. The combination, with the chuck, the turning-down tool, the screw-cutting die, and the pointing-tool, of the automatic mechanism for bringing said tools into action in the order above named and in the manner hereinbefore described.

7. The combination, with the chuck, the

chuck-spindle, the cam-shaft, the cam for relieving and restoring the bite of the chuck-jaws, and the mechanism through which the cam controls the said chuck-jaws, of the swinging length-gage mounted upon a stationary part of the machine-frame, and a rotating device—such as an eccentrically-placed pin—carried by a disk on the cam-shaft, and arranged to strike the tail of said length-gage to swing the same across the axis of the chuck, substantially as described.

8. The combination, with the chuck adapted to receive a long rod or screw-stock, and the feed weight and cord, of the slotted tube supported independently of the chuck for upholding the end of the rod or screw-stock outside the chuck-spindle, substantially as described.

9. The turning-down tool movable longitudinally and laterally with respect to the screw-stock, in combination with the mechanism for moving the said tool slightly backward at the end of its cutting action, and then shifting it aside, substantially as described.

10. The combination, with the chuck, the longitudinal slide, the turning-down tool, the screw-cutting die placed immediately behind the turning-down tool, and the cam and connections for operating said slide to bring said tools into action successively and by the same forward motion, of the separate cam and its connections for moving aside the turning-down tool at the end of its cutting action, substantially as described.

11. The combination, with the rock-shaft supporting the turning-down tool, of the nut or sleeve engaging the said shaft for rocking the same and imparting thereto a slight end motion in its bearings, substantially as described.

12. The combination, with the main slide, of the screw-cutting die, the auxiliary slide forming a support for said die, and movable in ways of the main slide, and the pointing-tool supported on said main slide, substantially as described.

13. The combination of the rotating sleeve and clutch-piece for revolving the die with the rotating shaft inclosed in said sleeve, the non-rotating clutch-piece surrounding said sleeve, and the clutch-piece revolved by said shaft, substantially as described.

14. The hollow screw-cutting die having cutting-jaws formed integral or in one piece therewith, and provided with an exterior flange at the base for securing it in position in its support, substantially as described.

15. The herein-described automatic screw-machine, comprising the chuck adapted to receive a long rod or screw-stock, the length-gage, the turning-down tool, the screw-cutting die, the pointing-tool, the automatic mechanism for releasing and restoring the bite of the chuck-jaws, the means for advancing the long rod or screw-stock, the automatic mechanism for operating the length-gage, and the automatic mechanism for operating the cutting-off tool,

in combination with the longitudinal slide carrying the turning-down tool, the screw-cutting die, and the pointing tool, the automatic mechanism for reciprocating said slide, the 5 automatic mechanism for revolving and holding stationary the die, and the automatic mechanism for moving aside the turning-down tool and for returning the same, substantially as described.

10 16. In the screw-cutting die having cutting jaws formed in one piece with the body of the die and held in by pressure, the compressing means bearing mainly upon the front or cutting side of said jaws, so that the rear or far- 15 ther part may spring out more or less, and thereby give a slight twist to the jaws, substantially as described.

17. The combination, in a screw-cutting die, of the jaws formed all in one piece, with the 20 compressing-ring having bearings upon said jaws mainly over the front or cutting edges

instead of over the whole width, substantially as described.

18. In the screw-cutting die, the jaws cut away on the outside so as to leave them thick- 25 est at points opposite the front or cutting edges, substantially as and for the purpose described.

19. The screw-cutting die comprising the jaws formed in one piece and screw-threaded 30 on their exterior, and cut away so as to leave threaded bearing-surfaces only opposite the front or cutting edges, in combination with the internally-threaded compressing-ring, substantially as described. 35

In testimony whereof I have signed this specification in the presence of two subscribing witnesses.

ALLEN JOHNSTON.
